United States Patent Office

Des. 208,188
Patented Aug. 1, 1967

208,188

PANTY GIRDLE

Herbert Barg, Merion, Pa., assignor to True Form Foundations, Inc., Darby, Pa., a corporation of Pennsylvania

Filed June 15, 1966, Ser. No. 2,679

Term of patent 14 years

(Cl. D2—4)

FIG. 1

FIG. 2

FIG. 3

FIG. 4

FIG. 6

I claim:

The ornamental design for a panty girdle, substantially as shown.
